United States Patent Office

Des. 186,668

Patented Nov. 17, 1959

186,668

TELEPHONE STAND

Martin J. Stevko, Chicago, Ill., assignor to General Telephone Laboratories, Incorporated, Northlake, Ill., a corporation of Delaware

Application June 2, 1958, Serial No. 51,145

Term of patent 14 years

(Cl. D26—14)

FIG. 1

FIG. 2

FIG. 3

Fig. 4

Fig. 1 is a front perspective view of a telephone stand showing my new design;

Fig. 2 is a perspective view from the left side of Fig. 1;

Fig. 3 is a perspective view taken from the left rear of Fig. 1; and

Fig. 4 is a front elevational view of Fig. 1.

The broken line showing of the handset is for illustrative purposes only.

I claim:

The ornamental design for a telephone stand, substantially as shown and described.
